UNITED STATES PATENT OFFICE

ROBERT MIEHLE, OF CHICAGO, ILLINOIS.

COMBINATION TWO-COLOR AND PERFECTOR PRINTING-PRESS.

1,293,855.

Specification of Letters Patent.

Patented Feb. 11, 1919.

Application filed February 21, 1917. Serial No. 150,009.

To all whom it may concern:

Be it known that I, ROBERT MIEHLE, a citizen of the United States, residing at Chicago, in the county of Cook and State of Illinois, have invented a certain new and useful Improvement in Combination Two-Color and Perfector Printing-Presses, of which the following is a full, clear, concise, and exact description.

10 My invention relates to rotary printing presses and has a number of objects and advantages in view. One feature of my invention resides in the employment of independent gears that are connected with the cylinders of a printing couple whereby these cylinders are permitted to preserve their proper printing relation substantially uninfluenced by the gearing which is employed to drive them and without slippage of either 15 cylinder with reference to the other that would cause rubbing action upon the form or printing surface upon the printing cylinder.

20 In practising this feature of my invention the axes of rotation of the cylinders of the printing couple are preferably normally fixed, the printing cylinder having a printing and a non-printing portion each such portion corresponding to the impression 25 portion of the impression cylinder, and gearing for rotating the impression cylinder in unison with the printing cylinder. This gearing includes the independent gears 30 that are connected with the cylinders of the 35 couple.

Another feature resides in providing 40 gearing for driving the cylinders of a two-color or perfecting press which includes independent gears that are connected with the respective cylinders whereby these cylinders are permitted to preserve their proper printing relation substantially uninfluenced by the gearing which is employed to drive them and without slippage of any cylinder 45 with reference to its related cylinders that would cause smutting or improper register upon the printed sheets, or wear on the plates.

50 Other features reside in the employment of independent means for driving the inking mechanism, the tripping mechanism, and the feed board moving mechanism which operates to periodically move the feed-board away from its impression cylinder to allow 55 the printed surfaces of the sheets to pass beneath the guide tongues upon the feed-

board in a manner to prevent the tongues from marring the printing whereby the actuation of these mechanisms cannot interfere with the maintenance of the proper 60 printing and registering relation of the cylinders.

Another feature resides in the employment and arrangement of gearing of the above described character in a two-couple 65 press and in providing means whereby one couple of the press may be adjusted for two color printing, *i. e.*, printing twice upon the same side of the sheet, or for perfecting printing, *i. e.*, printing once on each side of 70 the sheet, the cylinders being driven by independent gearing and the inking mechanisms, the tripping mechanism, and the feed board moving mechanisms being driven by independent means as above described. 75

In practising this convertible feature I employ two impression cylinders adapted to be brought into impression relation with one of the printing cylinders, and a supplemental feature to the above resides in providing means for varying the timing of the tripping mechanism to properly trip this couple in proper timed relation with either impression cylinder. 80

All of the above mentioned features contemplate a common means for driving the individual independent means in timed relation, and other features reside in the arrangement and construction of the various elements whereby the same are compactly 85 correlated without interfering with their proper functions or rendering the press inconvenient for the operator, the arrangement and provision of means for converting the two-couple press being such that the adjustments may be made quickly and easily. 90

The press of my invention is also desirably equipped with registering mechanism upon the cylinders of each printing couple, each such cylinder carrying an element of 100 such mechanism, the construction of the same being such that the adjustment of the same may be quickly made and with precision.

I will explain my invention more fully by 105 reference to the accompanying drawings showing the preferred embodiment thereof and in which Figure 1 is a view taken from the main gear side of the press, parts being broken away in order that characteristics of 110 construction may be more fully revealed, other parts of the press which are well

known to those skilled in the art being omitted; Fig. 2 is a plan view, partially in section, illustrating the preferred gearing arrangement; Fig. 3 illustrates one relationship of the form cylinders, impression cylinders, and transfer cylinders, this arrangement being employed when the press is adjusted to become a "perfector" press by which both sides of a sheet are printed upon, 5 Figs. 1 and 2 illustrating the gearing arrangement that is employed in the adjustment illustrated by Fig. 3; Fig. 4 illustrates another relationship of the form cylinders, impression cylinders, and transfer cylinders, 10 this arrangement being employed when the press is adjusted to be a two color press printing on the same side of each sheet; and Fig. 5 is a view partially in section and partially in end elevation of tripping mechanism that may be employed.

Like parts are indicated by similar characters of reference throughout the different figures.

The invention will first be described in connection with the arrangement as it is illustrated in Figs. 1, 2 and 3 that show a perfector press, one by which each sheet has both of its sides printed upon. A main driving pinion shaft 1 carries a pinion 2 which 25 is in mesh with the main driving spur gear wheel 3 which is fixed with respect to the stub shaft 3¹. This stub shaft is journaled in the frame of the machine to have a fixed axis of rotation for the gear wheel 3, that turns 30 with the stub shaft. The spur gear 3 is in mesh with spur gear 4 whose hub 5 is mounted to turn upon a sleeve 6 fixed to the frame of the machine, this sleeve confining gear 4 to a fixed axis of rotation with respect to the 35 frame of the machine. A second spur gear 7 (Fig. 2) is permanently fixed with respect to gear 4 by any suitable means, such for example as the bolts 8. Gear 7 is in mesh with a gear 9 whose hub is fixedly secured to the 40 shaft 10 of the first impression cylinder 11. A spur gear 12 is also brought into fixed relation with the spur gear 4 by means of the bolts 8. This gear 12 is in mesh with a spur gear 13 which in turn is in mesh with a spur gear 14 whose hub is in fixed connection with 45 the shaft 15 of the second impression cylinder 16. The first printing or form or plate cylinder 17 is fixed upon the shaft 18 that fixedly carries a spur gear 19 which is in 50 mesh with a spur gear 20 loose upon the hub of the gear 9. Gear 20 is in mesh with the broad faced gear 7. The second printing or form or plate cylinder 21 is fixed upon a shaft 22 that fixedly carries a spur gear 24¹ which is in mesh with a spur gear 24 that is 55 loosely mounted upon the hub of gear 14 and which meshes with gear 23 affixed to the gear 13. Gears 23 and 13 are, in Figs. 1 and 3, shown as being tied together by means of 60 bolts 25 to form a composite gear, an addi-

tional spur gear 23¹ being included in this composite gear between the gears 23 and 13. The first transfer cylinder 26 is fixedly secured to a shaft 27 upon which is fixed the spur gear 13. The second transfer cylinder 70 28 is fixed upon the shaft 29 to which is fixed the spur gear 30 which meshes with the gear 13.

As viewed in Fig. 3, the first impression cylinder 11 turns in a counter-clockwise direction while the first printing cylinder 17 associated therewith turns in a clockwise direction. The second impression cylinder 16 turns in a clockwise direction while the second printing cylinder 21 associated therewith turns in a counter-clockwise direction.

The first and second printing cylinders 17 and 21 are rotated in opposite directions (note the arrows in full lines on the printing cylinders in Fig. 3) as they could be 85

driven by meshing gears carried by these printing cylinders but which gears are preferably not employed. Gearing that is desirably employed for effecting such rotation of the printing cylinders and their associate impression cylinders is included in

distinct trains driven by the common gear 4 coupled and turning with gears 7 and 12 between which the gear 4 is disposed. Gear 7 is a broad faced gear which is in mesh 95

with the two independent gears 9 and 20, gear 9 being fixed upon the shaft 10 of the first impression cylinder and gear 20 being loosely mounted on the hub of gear 9

around the shaft 10 and meshing with gear 19 fixed on shaft 18 of the first printing cylinder. Thus does gear 4 independently 100 drive the independent gears 9 and 20 that respectively effect the rotation of the first impression cylinder 11 and the first printing cylinder 17, these independent gears being upon one side of the gear 4.

The independent gears 14 and 24 that respectively drive the second impression cylinder 16 and second printing cylinder 21 are upon the 105 other side of gear 4, the gear 14 being fixed upon the shaft 15 of the second impression cylinder and gear 24 being loosely mounted on the hub of gear 14 around the shaft 15 and meshing with gear 24¹ fixed

on shaft 22 of the second printing cylinder, gear 24¹ being mounted upon shaft 22 as gear 19 is mounted upon shaft 18, these gears 14 and 24 being in planes distinct

from the gears upon the first side of gear 4. While gear 7 is fixed with respect to gear 4 upon one side thereof and directly but independently drives the independent gears 9 and 20, the gear 12 fixed with respect to and upon the other side of the gear 125 4 independently drives the independent gears 14 and 24 through the intermediation of the composite gear 13, 23 which is mounted to turn upon the shaft 27, by which indirect drive of the independent gears 14 and 130

24 the second impression cylinder 16 is rotated oppositely to the first impression cylinder 11 and the second printing cylinder 21 is rotated oppositely to the first printing cylinder 17. By my indirect driving gearing above described I am enabled to obtain a freer rolling peripheral contact of the cylinders of each printing couple which is as free as possible from that influence of the 10 gearing which tends to disturb the desired printing relation of the members of each printing cylinder and I also minimize any disturbing influences of the members of either printing couple upon the printing relation between the members of the other printing couple.

In accordance with my invention, the spur gear fixed upon each cylinder is not in mesh with the spur gear fixed upon any 20 other cylinder either of its own printing couple or of the other printing couple since the central source of power (the gear 4) is common to the independent gears 9 and 20 which respectively pertain to the first impression cylinder 11 and the first printing cylinder 17 while this same central source of power (the gear 4) is common to the independent gears 14 and 24 which respectively pertain to the second impression cylinder 16 and the second printing cylinder 21. By means of my gearing the distance between the shafts 18 and 22 is not determined by the gearing that drives the printing cylinders upon these shafts, on which 30 account I am enabled relatively to locate these shafts and the printing cylinders thereupon as desired, in establishing the relation between these printing cylinders and the impression cylinders complementary thereto and without meshing the impression cylinder gear with its associate printing cylinder gear.

The printing or form cylinders 17 and 21 are respectively individual to the impression cylinders 11 and 16. The sheets to be printed upon are fed to the first impression cylinder 11 from the feed board 31. The grippers 32 upon the first impression cylinder 11 takes the sheet, numbered 33, from 40 the feed board and carry it around through the line 34 joining the centers of the shafts 10 and 15 to the line 34¹ joining the centers of the shafts 10 and 18 when the first printing operation is initiated, the form 35 upon 50 the first printing cylinder then having printing relation with the first side of the sheet 33 upon the cylinder 11, it being understood that each printing cylinder has a printing portion or form that corresponds 60 to the impression portion of the corresponding impression cylinder in the printing operation and a blank portion which corresponds to such impression portion in the non-printing operation. The first printing 65 operation upon sheet 33 thus initiated con-

tinues during the first revolution of the first impression cylinder and of a part of the second revolution thereof (beginning with the time the impression cylinder 11 received the sheet thereupon) until the form 35 upon 70 the first printing cylinder completes the printing upon the first side of the sheet 33. During the second revolution of the first impression cylinder 11 the grippers 36 upon the second impression cylinder 16 take the 75 sheet 33 being printed upon by the form 35 of the first printing cylinder 17, the grippers 32 releasing the sheet and the grippers 36 taking the sheet when these grippers upon these cylinders 11 and 16 are adjacent 80 at the line 34 during the second revolution of the first impression cylinder 11.

When the grippers 36 have sufficiently passed the line 37 joining the centers of the shafts 15 and 22, the second printing operation upon sheet 33 commences (this second operation being upon the other or second side of the sheet), the form 38 upon the second printing cylinder 21 then having printing relation with the second side of the sheet 90 33 then upon the second impression cylinder 16. In Fig. 3, the second impression cylinder 16 and the second printing cylinder 21 are shown as coöperating to perform the second printing operation upon a sheet 39 95 that immediately preceded sheet 33. The second printing operation initiated upon sheet 33 continues during the first revolution of the second impression cylinder 16 (beginning with the time the cylinder took the 100 sheet) until the form 38 upon the second printing cylinder 21 completes the printing upon the second side of the sheet in a like manner as the second printing operation was performed upon the sheet 39 above described. 105 During the first revolution of the second impression cylinder 16 the grippers 40 upon the transfer cylinder 26 take the sheet 33 being printed upon by the form 38 of the second printing cylinder 21, the grippers 36 110 releasing the sheet and the grippers 40 taking the sheet when these grippers upon these cylinders 16 and 26 are adjacent during the printing revolution of the cylinder 16 and are at the line 42 joining the centers of shafts 15 and 27 (Fig. 3). When the grippers of the transfer cylinder 26 reach the line 42 joining the centers of shafts 27 and 29, and the grippers 43 upon transfer cylinder 28 also reach this line adjacent the 120 grippers 40 and take the sheet therefrom during the second printing operation upon the sheet. The grippers 43 may carry the sheet around in the first revolution of the cylinder 28 and discharge the sheet while the grippers 43 are passing over the tapes 44 in the second revolution of such grippers. Or the leading edge of the sheet may be directly deposited upon the tapes 44 in the first revolution of such grippers. The por- 130

tion of my invention thus far specifically described in connection with the accompanying drawings is a so-called "perfector" press in which there is included, in the preferred 5 form of such press, two printing cylinders rotating in opposite directions, two impression cylinders each individual to a printing cylinder, and gearing for rotating each impression cylinder a plurality of times per 10 revolution of its printing cylinder, each printing cylinder having a printing portion (such as the form 35 for cylinder 17 and form 38 for cylinder 21) corresponding to the impression portion of the corresponding 15 impression cylinder and a non-printing portion, the part unoccupied by a form, that also corresponds to the impression portion of the corresponding impression cylinder. By this arrangement the axes of rotation of 20 the cylinders of each printing couple may be normally fixed.

I will now describe the press of my invention as it is adjusted and arranged to enable it to be used in performing two printing operations upon the same side of a sheet and in different colors if desired, reference being had to Figs. 1, 2 and 3 and especially to Fig. 4 which clearly illustrates the adjustment and arrangement of the press for 30 two color printing on one side of a sheet.

In order that the press as it is exhibited in Fig. 3 may serve the new purpose, the cylinder 16 is arranged to be the sheet transfer cylinder and cylinder 26 is arranged to 35 be an impression cylinder, to which end the bands 45 that surround the cylinder 26 and which are provided with sharp projections or teeth for engaging and supporting the paper, are removed and may be transferred 40 to the cylinder 16 while the tympan packing 46 upon the cylinder 16 is removed and may be transferred to the cylinder 26, both cylinders 16 and 26 being provided with mechanism that readily permit the exchange of 45 these elements 45 and 46. The cylinder 16 is also raised out of printing relation with the second printing cylinder 21 and the cylinder 26 is lowered into printing relation with 50 this printing cylinder. For this purpose I desirably provide the illustrated adjusting mechanism for the boxes 47 of the shafts of these cylinders and this adjusting mechanism is also of service in determining the 55 relative positions of the cylinders whether or not it is employed in converting the press. Each cylinder has a box 47 at each end of its shaft that is movable vertically in guideways 48 formed in the press side frames but which boxes are normally held from movement by means of the lower adjusting screws 49 and the upper adjusting screws 50, these screws being in threaded engagement with the press frame and having butt engagement with the bottom and top faces of the boxes 60 positioned therebetween. Each of the lower

screws 49 is limited in its downward movement by a set screw stop 51 carried by the frame of the press and the abutment screws 50 pertaining to cylinders 16 and 26 are limited in their upward movement by the fixed 70 stops 52 secured upon the frame of the press. The stops 52 are so positioned that they define the positions of their cylinders when such cylinders are to be used as transfer cylinders, while the adjustable stops 51 define 75 the positions of the cylinders in their printing relation. When the cylinders 16 and 26 are adjusted to the positions illustrated in Fig. 4 the screws 50 pertaining to the cylinder 16 are unscrewed until they engage their 80 stops 52 whereafter the complementary screws 49 are screwed upwardly to bring the boxes 47 of cylinder 16 into engagement with the lower ends of the adjusted screws 50. In raising the cylinder 16 the unthreaded holes 85 53 in gears 24, 54 and 14 come into register with the threaded openings 55 in the gear 12, the bore of the sleeve 6 being cored out to afford space in which shaft 15 of the cylinder 16 may be moved to bring it into central 90 alignment with the exterior cylindrical bearing surface of the sleeve 6. The bolts 25 are now removed from their positions illustrated in Fig. 3 and are passed through the openings 53 and are screwed into the threaded opening 55. The gears 24, 54, 14, 12, 4 and 7 now become a common unitary gear. After the bolts 25 are removed the washer 56 upon the shaft 27 and the gear 23 are removed. The screws 49 of cylinder 26 are 100 now lowered until the lower ends of these screws engage the adjustable stops 51 whereafter the screws 50 of cylinder 26 are screwed down into engagement with the top side of the lowered boxes 47 of this cylinder 26. In adjusting the screws it is proper to have two attendants, one on each side of the press, for operating the cylinder adjusting screws of each cylinder at the same time. In the new 105 adjustment the impression and transfer cylinders 11, 16, 26 and 28 may rotate in the same direction in which these cylinders respectively rotate in the press as it is illustrated in Fig. 3. The direction of rotation of the printing cylinder 21, however, in the 110 arrangement shown in Fig. 4 should be opposite to the rotation of this cylinder in the arrangement of Fig. 3, a result which is secured by replacing the gear 23 upon the shaft 27 and meshing it with the gear 24' 115 after the cylinder 21 has been turned to bring it into its proper printing relation with the impression cylinder 26, the movement of the cylinder 16 out of impression relation with the cylinder 21 having unmeshed said gear 24' 120 and the movement of cylinder 26 into impression relation with cylinder 21 having brought said gear 23 in meshing relation with said gear 24' when said gear 23 is on the shaft of said cylinder 125 130

der 26. After the gear 23 is meshed with the gear 24¹ the washer 56 is secured to the shaft 27 to keep the gears 23, 23¹ and 13 in assembly. The axes of printing cylinders, 5 the impression cylinders, and the transfer cylinder 16 may be normally fixed but the printing cylinders may be tripped into and out of printing position by means of any suitable tripping mechanism provided for 10 each printing cylinder, such as that illustrated in Fig. 4. Each printing cylinder is normally dissociated from its tripping mechanism but is coupled therewith by a separate mechanism or the press attendant who 15 ordinarily has one foot key for each printing cylinder. The tripping mechanism employed may be of the general nature illustrated in my Patents 689,505, dated December 24, 1901, and 1,081,420, dated December 20 16, 1913 with necessary changes.

The foot key not shown is connected with a connecting link 57 that is connected with a rocker arm 57¹ that in turn is fixed upon a rod 57² and on which rod there is fixed a 25 cam arm 58 carrying a trip cam portion 58¹. Whenever the foot key is depressed the rod 57² of the corresponding tripping mechanism is turned to turn the cam arm 58 to move the upper end of the cam arm 30 downwardly to lower the hook 59 into engagement with the tooth c, the parts, k¹ of part k 59 and c constituting elements of a coupler that connects the corresponding 35 printing cylinder with its tripping cam d. The tripping cam d belonging to the first printing cylinder is rotated by the gear e upon which the cam is fixedly located, the gear e in turn being rotated by the pinion f upon the stud g fixed to the frame, the 40 pinion f being in fixed connection with the spur gear wheel h that is in mesh with the pinion 2¹ carried upon the other end of the shaft l opposite that which carries the pinion 2 and which latter pinion meshes with 45 gear wheel 3, this shaft passing through the machine from side to side. The tripping mechanisms for both printing cylinders are of similar construction, generally speaking, and similar parts are given similar characters of reference. The gear e of 50 the second printing cylinder tripping mechanism is driven by the intermediate gear e¹ that is driven by gear e, the intermediate gear e¹ being mounted to turn upon a fixed 55 stud that is carried by the frame of the machine. The cam groove d¹ in cam d engages a cam roller i upon an arm k loose on shaft l that passes from side to side of the machine and to which shaft the tooth c is fixed. 60 The roller i is mounted upon the stud i¹ upon the inner end of which the hook 59 is mounted to swing. Shaft l carries two eccentrics l¹ upon each of which a sliding box member l² rests, each sliding box member supporting the extension l³ of the cor-

responding printing cylinder shaft box l⁴, there being thus one eccentric l¹ in supporting relation to each printing cylinder shaft box l⁴. The arc a b of the cam groove is eccentric with the shaft d² of the cam. The cam roller i is not bodily moved while engaging this part of the cam groove whereby the arm k is then at rest. The hook 59 carries a cam roller m that may bear upon the operating tripping cam portion 58¹ 70 of the arm 58. The arm k carries stop pin o and hook 59 has a lug p, the elements o and p preventing the hook 59 from separating any further from the tooth c than illustrated. 80

Each pair of eccentrics l¹ upon the same shaft l has the position illustrated when the printing cylinder corresponding thereto is in its normal operating position, the centers of these eccentrics being normally positioned slightly to the left of the vertical line passing through the centers of the shaft l and the shaft of the corresponding printing cylinder and being between this line and the stationary stop pin q. As tooth c is in 90 fixed relation to the eccentrics l¹ the stop pin q holds the shaft l from counter-clockwise rotation to hold the corresponding printing cylinder in working position. The stop pin q illustrated is upon one side of the 95 press. There may be a similar stop pin on the other side of the press that is to be engaged by an arm fixed upon the other end of the shaft l and positioned similarly to the tooth c to take part in preventing the 100 turning of the shaft l and the eccentrics thereon. When the shaft l is turned clockwise the eccentrics l¹, being fixed upon the shaft, are also turned clockwise so that the corresponding printing cylinder is lowered 105 to non-printing position. This rotation of the shaft l and the eccentrics l¹ cannot occur until after the part 59¹ of hook 59 is 110 brought into position to enable it to be engaged with the lower side of the tooth c, following the depression of the foot key by the press attendant to lower the arm 58 and the cam part 58¹ thereon to permit the hook 59 to swing downwardly into the hook engaging position. Operative engagement of the part 59¹ of the hook 59 with the tooth c can only occur while the arcal portion a b of the cam groove d¹ is passing by the cam roller i, which is when the line b¹ is passing from the line a¹ to the position 115 of the line b¹. That is, the tripping may be effected only during the time the leading edge of the printing form travels through the arc a¹ b¹ and during the time the segment a b of the cam slot d¹ is passing by the roller i. When the cam roller i is in the 120 position of the cam groove d¹ between the side a of the arc a b and the shaft d², the cam roller i is drawn toward the shaft d² 125 to the position shown at the left of Fig. 4 130

in connection with the second printing cylinder. The part 59¹ of the hook 59 (assuming that the attendant has dropped the arm 58 to permit the hook 59 to engage the tooth *c*) pulls the tooth *c* in a clockwise direction whereby the eccentrics 7¹ are turned in a similar direction to permit the corresponding printing cylinder to be lowered by its own weight. When the roller *i* 10 is in the portion of the cam groove *d*¹ between the shaft *d*² and the side *b* of the arc *a* *b* the motion of the arm *k* is reversed whereupon the extension *k*¹ of the arm *k* pushes upon the lug *c*¹ carried by the tooth 15 *c* to turn the tooth *c* and the eccentrics 7¹ fixed with respect thereto counter clockwise back to the normal position illustrated in Fig. 4. In coming back to this position the eccentrics 7¹ raise the corresponding printing cylinder to working position. It is understood that the roller *m* (upon the hook 59) supports the hook while this roller *m* rides over the tripping cam portion 58¹ 20 when the arm 58 that carries this cam 58¹ is in the normal raised position illustrated and while the corresponding printing cylinder is in its normal operating position. The arm 58 may be lowered at any time but should this arm be lowered while the roller 25 *i* is not in the arcal portion *a* *b* of the cam slot *d*¹, the swinging end of the hook will ride upon the crown of the tooth *c* (see the lower left hand corner of Fig. 4) until the roller *i* is received in the arcal portion 30 *a* *b* of the cam groove *d*¹. In the arrangement illustrated in Fig. 4 the cam *d* is adjusted to constitute the press a two color press, the bolt *d*³ carried by the gear *e* of the second printing cylinder tripping mechanism being within the opening *d*⁴ in the 35 adjacent cam *d*, this bolt adjustment *d*³ pertaining only to the tripping cam mechanism of the second printing cylinder. When the press is to be adjusted to be a perfector press 40 45 the adjacent cam *d* is shifted to the position shown by dot and dash lines (Fig. 4) to bring the bolt hole *d*⁵ therein into register with the bolt hole *d*⁶ in said gear *e*, the bolt *d*³ then being inserted in the registering holes 50 *d*⁶ *d*⁵ to maintain the cam *d* in this new position with reference to said gear *e*. No such adjustment as this is required for the first printing cylinder tripping mechanism on which account the cam *d* and gear *e* pertaining to this tripping mechanism may be 55 integrally formed.

Still referring particularly to Fig. 4, the sheets to be printed upon are fed to the first impression cylinder 11 from the feed board 60 61. The grippers 32 upon the first impression cylinder 11 take the sheet, numbered 60, from the feed board and carry it around through the line 34 joining the centers of the shafts 10 and 15 to the line 34¹ joining the 65 centers of the shafts 10 and 18 when the first

printing operation is initiated, the form 35 upon the first printing cylinder then having printing relation with the sheet 60 upon the cylinder 11. The first printing operation upon sheet 60 thus initiated continues 70 during the first revolution of the first impression cylinder 11 and of part of the second revolution thereof (beginning with the time the impression cylinder 11 received the sheet) until the form 35 upon the first printing cylinder completes its printing upon the sheet 60. During the second revolution of the first impression cylinder 11 the grippers 36 upon cylinder 16, now a transfer cylinder, take the sheet 60 being printed upon by the form 35 of the first printing cylinder 17, the grippers 32 releasing the sheet and the grippers 36 taking the sheet when these grippers upon the cylinders 11 and 16 are adjacent at the line 34 during the second revolution of the first impression cylinder 11. In Fig. 4 the transfer of the sheet 60 from the cylinder 11 to the transfer cylinder 16 will not occur until the cylinders 11 and 16 have each made another revolution from the position there shown, a sheet 61 preceding the sheet 60 being held by the grippers 36 preparatory to transfer to the cylinder 26, now the second printing cylinder. During the second revolution of the transfer cylinder 16 from the position shown in Fig. 4 the grippers 40 upon the impression cylinder 26 take the sheet 60, the grippers 36 releasing the sheet and the grippers 40 taking the sheet when these grippers upon these cylinders 16 and 26 are adjacent during said second revolution of the cylinder 16 and are at the line 41 joining the centers of shafts 15 and 27 (Fig. 4). When the grippers 40 have sufficiently passed the line 62 that joins the centers of shafts 27 and 22, the second printing operation upon the sheet 60 commences, this second operation being upon the said side of the sheet previously 67 printed upon by the printing cylinder 17 since the transfer cylinder 16 causes the sheet to be taken by impression cylinder 26 with the printed or wet side outside to enable this same wet side to be printed upon by the second printing cylinder 21. The second impression cylinder 26 and the second printing cylinder 21 with its form surface 38 are shown as coöperating to perform the second printing operation upon a sheet 63 that immediately precedes sheet 61. The second printing operation initiated upon sheet 60 continues during the first revolution of the second impression cylinder 26 (beginning with the time this cylinder took the sheet) until form 38 upon the second printing cylinder 21 completes the second printing operation upon the same side of the sheet previously printed upon by the first printing cylinder 17. The grippers of the second impression cylinder 26 reach the 120 125 130

line 42 joining the centers of shafts 27 and 29 (Fig. 3), and the grippers 43 upon transfer cylinder 28 also reach this line adjacent the grippers 40 and take the sheet 5 therefrom during the second printing operation upon the sheet whereafter the sheet may be disposed of in either of two ways as described in connection with Fig. 3.

The press, rearranged as illustrated in Fig. 4, is a multi-couple, multi-cylinder printing press especially adapted for color printing and commonly known as a two color press and by which the same side of a sheet receives two successive impressions by 15 the printing operation of the two printing couples therupon.

The feed board or feed board section 31 is swingingly mounted at 64 and the extent to which the board 31 may swing 20 downwardly is adjustably determined by means of thumb screw stops 65 carried by the lugs 66 upon the press frame. The feed board 31 carries a rod 67 mounted to turn in brackets 68 carried by the feed board. 25 The rod 67 carries two feed board raising fingers 69 that bear at their outer ends upon the aforesaid lugs 66. An arm 70 is fixed upon that end of the rod 67 which is at the gear side of the press, this arm 67 projecting 30 outwardly so as to connect with the upper end of the lifting bar 71. This lifting bar has butt engagement at its lower end with the stud 72 fixed upon the cam arm 73 that is pivoted at 74. This cam arm carries a cam 35 roller 75 that rides upon a cam 76 fixed with respect to the gear 3. The lifting bar 71 carries an inclined guiding finger 77 which serves to guide the lifting bar into operating relation with the stud 72 when the feed board 40 is lowered and in position to enable this stud to engage the lifting bar when the roller 75 rides upon the cam 76. The effective length of the lifting bar is adjustable by making the part of the lifting bar which 45 is engaged by the stud 72 an added section 71¹ of such bar which is adjustable with relation to the stud. The adjusting means illustrated includes an adjusting screw 71² carried by the lug 71³ upon the section of the 50 bar which is connected with the arm 70, the lower end of this screw being connected with the adjustable bar section 71¹. Screws 71⁴ hold the section 71¹ in the position to which it is adjusted with reference to the stud 72. 55 When the wet side of the printed sheet upon the first impression cylinder approaches the forward ends of the feed guide tongues or fingers 78, the cam 76 engages the cam roller 75 to lift the feed board, said cam 60 roller turning upon the outer cam dwell 79 until the rear end of the sheet nearly reaches the front ends of the tongues 78 whereupon the cam portion 80 passes the roller 75 to allow this roller to come upon the lower cam dwell in time to position the feed board to

allow the grippers 32 to take the next sheet properly. By means of the adjustable section 71¹ of the lifting bar 71 the height to which the feed board is raised is adjustably determined to suit the nature of the stock. 70 Heavier stocks obviously require that the guide tongues 78 be raised higher than in the case of lighter stock to afford the necessary greater clearance between the tongues and printed surface.

It will be noted that the cam 76-80 is carried by the gear 3 which is independent, not being in mesh with the gears upon the cylinders of the first printing couple whereby the printing relation between these cylinders is not disturbed by the action of the cam mechanism upon the feed board.

The two color press illustrated in Fig. 4 may be adjusted to enable the grippers of the transfer cylinder 16 to transfer the 85 printed sheet in the first revolution thereof as shown in Fig. 3 after receiving the sheet from the first impression cylinder (instead of in the second revolution of the transfer cylinder 16 as before described and illustrated in Fig. 4) to the second impression cylinder 26. The time that the grippers of the second impression cylinder 26 take the sheet from the transfer cylinder 16 is therefore changed so as to take the sheet from the 95 grippers on the transfer cylinder 16 in the aforesaid first revolution of this cylinder 16. It follows that adjustment should be made of the second printing cylinder 21 to correspond to the altered time relation of the 100 second impression cylinder 26 to establish proper printing relation between these cylinders of the second printing couple. This adjustment of the second printing cylinder is effected by revolving it one-half a revolution 105 while the other cylinders are stationary and the tripping cam mechanism pertaining to this printing cylinder 21 is correspondingly adjusted a half revolution which is accomplished by removing the bolt *d*³ and placing 110 it in a new hole in the cam *d* of this tripping mechanism which is diametrically opposite the hole in this cam that previously received the bolt.

The transfer cylinder 28 may be moved 115 bodily to and from cylinder 26 by cam 81 (carried by the independent gear 3) and may operate the cam lever mechanism 82 which shifts the arm 83 that is carried by the eccentric 84, in which eccentric the shaft 120 of cylinder 28 is mounted. This adjustment and mechanism for accomplishing it is disclosed in my co-pending application Serial No. 146,830, filed February 3, 1917.

Each printing cylinder 17 and 21 is inked 125 by means of form rollers 83 which are distributed in pairs or couples, each couple having a vibrating distributing roller 84 in the usual relation to the form roller. Each distributing roller has the usual gear 85 driven 130

by the usual pinion 86. These pinions 86 are broad faced and turn loosely upon the shafts 87 fixed in the frame of the press.

The inking rollers pertaining to printing cylinder 17 are driven by the gear 88 (that is in mesh with the adjacent pinion 86) which in turn is driven by the gear 9, rotatably mounted on the hub of gear 9 that in turn is driven by the broad faced gear 7, this 10 gearing being independent of the gears that are connected with the printing cylinder 17 and impression cylinder 11 for driving these cylinders. The inking rollers pertaining to the printing cylinder 21 are driven by the 15 gear 90 (that is in mesh with the adjacent pinions 86 which is rotatably mounted on the hub of gear 24¹) and which (in Figs. 2 and 3) in turn is driven by the gear 54 that in turn is driven by the gear 23¹ that is fixedly 20 coupled with the gear 13 which is driven by gear 12, this gearing that drives the inking rollers pertaining to the second printing cylinder 21 being independent of the gears that are connected with the printing cylinder 25 25 and impression cylinder 16 for driving these cylinders. According to the adjustment illustrated in Fig. 4 and Fig. 2 the gear 12 drives the gear 54 by being fixedly coupled therewith by the bolts 25 that are 30 transferred to the holes 53 and 55, but it will be noted that in this adjustment the cylinder 16 is raised to its upper position, in which position the gear 54 is out of mesh with the gear 90. In this adjustment said gear 90 is 35 in mesh with the gear 23¹, due to the fact that the cylinder 26 has been moved to its lowermost position for impression engagement with cylinder 21, said gear 23¹ being driven by gear 54, whereby the direction of 40 rotation of the inking rollers that pertain to the second printing cylinder 21 is reversed at the same time the rotation of the second printing cylinder is reversed, these inking rollers still being rotated by gearing that is 45 independent of the gears that are connected with the cylinders of the second printing couple. By means of the independent gearing or trains of gears that operate the inking mechanism pertaining to the printing 50 cylinders the operation of the inking mechanism is prevented from disturbing the printing relation between the printing cylinders and their respective impression cylinders as little as possible.

55 Referring first particularly to Figs. 3 and 4, the printing cylinder 17 has one registering segment 91 coöperating with a registering segment 92 upon the corresponding impression cylinder 11. The printing cylinder 60 21 has two registering segments 93, 94, the registering segment 93 being complementary to the registering segment 95 provided upon the cylinder 26 when the press is adjusted to operate as a two color press, Fig. 4, this 65 segment 93 being at one end of the form 38.

The registering segment 94 is complementary to the registering segment 96 provided upon the cylinder 16 when the press is adjusted to operate as a two color press, Fig. 3. Each registering segment desirably has its base 70 resting upon a ledge carried by the corresponding cylinder, Fig. 4. For example, registering segment 93 has its base resting upon the ledge 97 while the registering segment 95 has its base resting upon the ledge 75 98. The complementary registering segments pertaining to the cylinders of each couple are adjustable transversely of the axis of rotation of such cylinders whereby they may be caused so to mesh that there will be no 80 backlash or lost motion between the teeth thereof. This adjustment may be effected by means of liners at the bases of the registering segments. The registering segments may be adjusted simultaneously as by means 85 of bolt and slot connections such as are illustrated at 99, Fig. 4. By means of this adjustment registering segments may be placed in selected positions with respect to the meshing gears that drive the cylinders so 90 that the registering segments will not crowd the teeth of those gears in either direction.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent 95 the following:

1. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; and a gear common to said trains of gears for 105 operating them.

2. A rotary printing press including two printing couples each comprising an impression cylinder and a printing cylinder; inking roller mechanism for each printing cylinder; a train of gears for each of the aforesaid cylinders for operating them; a train of gears for operating each inking roller mechanism; and a gear common to 115 said trains of gears for operating them.

3. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; and a gear common to said trains of gears for operating them; the shaft of one 125 of said cylinders carrying a gear included in the train that drives the other cylinder. 130

4. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; and a gear common to said trains of gears for operating them, the shaft of the 5 impression cylinder carrying a gear included in the train that drives the printing cylinder. 5. A rotary printing press including two printing couples each comprising an impression cylinder and a printing cylinder; 10 inking roller mechanism for each printing cylinder; a train of gears for each of the aforesaid cylinders for operating them; a train of gears for operating each inking roller mechanism; and a gear common to 15 said trains of gears for operating them, the shaft of the impression cylinders carrying gears included in the trains that drive the respective printing cylinders, said common gear being disposed about the shaft of one of the cylinders of the press. 11. A rotary printing press including a printing couple comprising an impression cylinder and a printing cylinder; a train of gears for each of the aforesaid cylinders for operating them; and a gear common to said trains of gears for operating them, the shaft of the impression cylinder carrying a gear included in the train that drives the printing cylinder, said common gear being disposed about the shaft of one of the cylinders of the press. 12. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; and a gear common to said trains of gears for operating them, the shaft of the impression cylinder carrying a gear included in the train that drives the printing cylinder, said common gear being disposed about the shaft of one of the cylinders of the press. 13. A rotary printing press including two printing couples each comprising an impression cylinder and a printing cylinder; inking roller mechanism for each printing cylinder; a train of gears for each of the aforesaid cylinders for operating them; a train of gears for operating each inking roller mechanism; and a gear common to said trains of gears for operating them, the shaft of the impression cylinders carrying gears included in the trains that drive the printing cylinders, said common gear being disposed about the shaft of one of the cylinders of the press while gears in the inking roller mechanism, impression cylinder and printing cylinder operating trains are also disposed about the shaft about which the common gear is disposed. 14. A rotary printing press including a printing couple comprising an impression cylinder and a printing cylinder; a train of gears for each of the aforesaid cylinders for operating them; and a gear common to said trains of gears for operating them, the 20 25 30 35 40 45 50 55 60 65 70 75 80 85 90 95 100 105 110 115 120 125 130
8. A rotary printing press including two printing couples each comprising an impression cylinder and a printing cylinder; a train of gears for each of the aforesaid cylinders for operating them; and a gear common to said trains of gears for operating them, the shafts of the impression cylinders carrying gears included in the trains that drive the printing cylinders. 9. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; and a gear common to said trains of gears for operating them, the shaft of the impression cylinder carrying a gear included in the train that drives the printing cylinder, said common gear being disposed about the shaft of one of the cylinders of the press while gears in the inking roller mechanism, impression cylinder and printing cylinder operating trains are also disposed about the shaft about which the common gear is disposed. 10. A rotary printing press including two printing couples each comprising an impression cylinder and a printing cylinder; inking roller mechanism for each printing cylinder; a train of gears for each of the aforesaid cylinders for operating them; and a gear common to said trains of gears for operating them, the

shaft of the impression cylinder carrying a gear included in the train that drives the printing cylinder, said common gear being disposed about the shaft of one of the cylinders of the press while gears in the impression cylinder and printing cylinder trains are also disposed about the shaft about which the common gear is disposed.

15. A rotary printing press including two printing couples each comprising an impression cylinder and a printing cylinder; a train of gears for each of the aforesaid cylinders for operating them; and a gear common to said trains of gears for operating them, the shafts of the impression cylinders carrying gears included in the trains that drive the printing cylinders, said common gear being disposed about the shaft of one of the cylinders of the press while gears in the impression cylinder and printing cylinder trains are also disposed about the shaft about which the common gear is disposed.

16. A rotary printing press including a printing couple comprising an impression cylinder and a printing cylinder; a train of gears for each of the aforesaid cylinders for operating them; a gear common to said trains of gears for operating them; tripping mechanism for breaking the printing relation between said printing cylinder and said impression cylinder; and means having operable connection with said common gear and said tripping mechanism for operating said tripping mechanism in timed relation with said common gear.

17. A rotary printing press including a printing couple comprising an impression cylinder and a printing cylinder; a train of gears for each of the aforesaid cylinders for operating them; inking roller mechanism for said printing cylinder; a train of gears for operating the inking roller mechanism; a gear common to said trains of gears; tripping mechanism for breaking the printing relation between said printing cylinder and said impression cylinder; and means having operable connection with said common gear, and said tripping mechanism for operating said tripping mechanism in timed relation with said common gear.

18. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; a gear common to said train of gears for operating them; the shaft of the impression cylinder carrying a gear included in the train that drives the printing cylinder; tripping mechanism for breaking the printing relation between said printing cylinder and said impression cylinder; and means having operable connection with said common gear and said tripping mechanism for operating said tripping mechanism in timed relation with said common gear.

erable connection with said common gear and said tripping mechanism for operating said tripping mechanism in timed relation with said common gear.

19. A rotary printing press including a printing couple comprising an impression cylinder and a printing cylinder; a train of gears for each of the aforesaid cylinders for operating them; a gear common to said trains of gears for operating them; the shaft of the impression cylinder carrying a gear included in the train that drives the printing cylinder; tripping mechanism for breaking the printing relation between said printing cylinder and said impression cylinder; and means having operable connection with said common gear and said tripping mechanism for operating said tripping mechanism in timed relation with said common gear.

20. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; a gear common to said trains of gears for operating them; tripping mechanism for breaking the printing relation between said printing cylinder and said impression cylinder; and means having operable connection with said common gear for operating said tripping mechanism in timed relation with said common gear.

21. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; a gear common to said trains of gears for operating them; tripping mechanism for breaking the printing relation between said printing cylinder and said impression cylinder; and means having operable connection with said common gear for operating said tripping mechanism in timed relation with said common gear.

22. A rotary printing press including a printing couple comprising an impression cylinder and a printing cylinder; a train of gears for each of the aforesaid cylinders for operating them; a gear common to said trains of gears for operating them; tripping mechanism for breaking the printing relation between said printing cylinder and said impression cylinder; and means having operable connection with said common gear for operating said tripping mechanism in timed relation with said common gear.

23. In a rotary printing press, the combination with a printing cylinder; of two

- impression cylinders; means for bringing either of said impression cylinders into impression relation with said printing cylinder; tripping mechanism adapted to trip said printing cylinder from its impression relation with either of said impression cylinders; said tripping mechanism including a timing cam driven in timed relation with said printing cylinder; and means for changing the timing of said cam relative to said printing cylinder whereby the printing cylinder may be tripped at the proper time relatively to the impression cylinder with which it may be in impression relation.
24. In a rotary printing press, the combination with a printing cylinder; of two impression cylinders; means for adjusting said first impression cylinder into and out of impression relation with said printing cylinder; means for adjusting said other impression cylinder into and out of impression relation with said printing cylinder; and tripping mechanism for said printing cylinder adapted to trip the same from its impression relation with either of said impression cylinders; said tripping mechanism including a timing cam driven in timed relation with said printing cylinder; and means for changing the timing of said cam relative to said printing cylinder whereby the printing cylinder may be tripped at the proper time relatively to the impression cylinder with which it may be in impression relation.
25. In a rotary printing press, the combination with a printing cylinder; of two impression cylinders; the first of said cylinders being adapted to receive a sheet and to transfer the same to the other impression cylinder, said other impression cylinder being adapted to receive the sheet from said first impression cylinder; means for bringing either of said impression cylinders into impression relation with said printing cylinder; and tripping mechanism for said printing cylinder adapted to trip said printing cylinder from its impression relation with either of said impression cylinders; said tripping mechanism including a timing cam driven in timed relation with said printing cylinder; and means for changing the timing of said cam relative to said printing cylinder whereby the printing cylinder may be tripped at the proper time relatively to the impression cylinder with which it may be in impression relation.
26. In a rotary printing press, the combination with a printing cylinder; of two impression cylinders, the first of said cylinders being adapted to receive a sheet and to transfer the same to the other impression cylinder, said other impression cylinder being adapted to receive the sheet from said first impression cylinder; means for adjusting said first impression cylinders into and
- out of impression relation with said plate cylinder; means for adjusting said other impression cylinder into and out of impression relation with said printing cylinder; and tripping mechanism for said printing cylinder adapted to trip the same from its impression relation with either of said impression cylinders; said tripping mechanism including a timing cam driven in timed relation with said printing cylinder; and means for changing the timing of said cam relative to said printing cylinder whereby the printing cylinder may be tripped at the proper time relatively to the impression cylinder with which it may be in impression relation.
27. A rotary printing press including a printing couple comprising an impression cylinder and a printing cylinder; a train of gears for each of the aforesaid cylinders for operating them; a gear common to said trains of gears for operating them; a feed board positioning mechanism; and an operable connection between said common gear and said last mentioned mechanism for operating said mechanism in timed relation with said common gear.
28. A rotary printing press including a printing couple comprising an impression cylinder and a printing cylinder; inking roller mechanism for the printing cylinder; a train of gears for each of the aforesaid cylinders for operating them; a train of gears for operating the inking roller mechanism; a gear common to said trains of gears; a feed board positioning mechanism; and an operable connection between said common gear and said last mentioned mechanism for operating said mechanism in timed relation with said common gear.
29. A rotary printing press including a printing couple comprising an impression cylinder and a printing cylinder; a train of gears for each of the aforesaid cylinders for operating them; a gear common to said trains of gears for operating them; a feed board positioning mechanism; a tripping mechanism; and operable connections between said feed board positioning mechanism and said tripping mechanism and said common gear for operating said tripping mechanism and said feed board positioning mechanism in timed relation with said common gear.
30. In a rotary printing press the combination with a printing cylinder; of two impression cylinders; means for adjusting the first impression cylinder into and out of impression relation with said printing cylinder; means for adjusting the other impression cylinder into and out of impression relation with said printing cylinder; a first gear in fixed relation with said printing cylinder; a second gear in fixed relation with the first impression cylinder; a third gear in

- fixed relation with the other impression cylinder and constantly meshing with said last mentioned gear; a fourth gear movably mounted; a fifth gear movably mounted and 5 constantly in mesh with said fourth gear, said fourth and fifth gears being adapted to mesh with said first gear when their respective impression cylinders are in impression relation with said printing cylinder, said 10 fourth and fifth gears being adapted to be rotatorially fixed relatively to their respective impression cylinders.
31. In a rotary printing press the combination with a printing cylinder; of two impression cylinders; means for adjusting the first impression cylinder into and out of impression relation with said printing cylinder; means for adjusting the other impression cylinder into and out of impression relation 15 with said printing cylinder; a first gear in fixed relation with said printing cylinder; a second gear in fixed relation with said first impression cylinder; a third gear in fixed relation with said other impression cylinder into and out of impression relation with said printing cylinder; a first gear in fixed relation with said printing cylinder; a second gear in fixed relation with said first impression cylinder; a third gear in fixed relation with said other impression cylinder, and constantly meshing with said last mentioned gear; and a driving gear constantly in mesh with said third gear and adapted to be rotatorially fixed relatively to said second gear.
32. In a rotary printing press the combination with a printing cylinder; of two impression cylinders, the first impression cylinder being adapted to receive a sheet and to transfer the same to the other impression cylinder, said other impression cylinder being adapted to receive the sheet from said first cylinder; means for adjusting the first impression cylinder into and out of impression relation with said printing cylinder; 30 means for adjusting the other impression cylinder into and out of impression relation with said printing cylinder; a first gear in fixed relation with said printing cylinder; a second gear in fixed relation with said first impression cylinder; a third gear in fixed relation with said other impression cylinder and constantly meshing with said last mentioned gear; a fourth gear movably mounted and adapted to be moved into and out of mesh with said first gear; a fifth gear movably mounted and adapted to be moved into and out of mesh with said first gear and constantly in mesh with said fourth gear, said fourth and fifth gears being adapted to be rotatorially fixed relatively to their respective impression cylinders.
33. In a rotary printing press the combination with a printing cylinder; of two impression cylinders, the first impression cylinder being adapted to receive a sheet and to transfer the same to the other impression cylinder, said other impression cylinder being adapted to receive the sheet from said 45 first cylinder; means for adjusting the first impression cylinder into and out of impression relation with said printing cylinder; a first gear in fixed relation with said printing cylinder; a second gear in fixed relation with said first impression cylinder; a third gear in fixed relation with said other impression cylinder and constantly meshing with said last mentioned gear; a fourth gear movably mounted and adapted to be moved into and out of mesh with said first gear; a fifth gear movably mounted and adapted to be moved into and out of mesh with said first gear and constantly in mesh with said fourth gear, said fourth and fifth gears being adapted to be rotatorially fixed relatively to their respective impression cylinders.
34. In a rotary printing press the combination with a printing cylinder; of two impression cylinders, the first impression cylinder being adapted to receive a sheet and to transfer the same to the other impression cylinder, said other impression cylinder being adapted to receive the sheet from said first cylinder; means for adjusting the first impression cylinder into and out of impression relation with said printing cylinder; a first gear in fixed relation with said printing cylinder; a second gear in fixed relation with said first impression cylinder; a third gear in fixed relation with said other impression cylinder and constantly meshing with said fourth gear, said fourth and fifth gears being adapted to be rotatorially fixed relatively to their respective impression cylinders.
35. In a rotary printing press the combination with a printing cylinder; of two impression cylinders, the first impression cylinder being adapted to receive a sheet and to transfer the same to the other impression cylinder, said other impression cylinder being adapted to receive the sheet from said first cylinder; means for adjusting the first impression cylinder into and out of impression relation with said printing cylinder; a first gear in fixed relation with said printing cylinder; a second gear in fixed relation with said first impression cylinder; a third gear in fixed relation with said other impression cylinder and constantly meshing with said last mentioned gear; a fourth gear movably mounted and adapted to be moved into and out of mesh with said first gear; a fifth gear movably mounted and adapted to be moved into and out of mesh with said first gear and constantly in mesh with said fourth gear, said fourth and fifth gears being adapted to be rotatorially fixed relatively to their respective impression cylinders.

- cylinder into and out of impression relation with said printing cylinder; a first gear in fixed relation with said printing cylinder; a second gear in fixed relation with said first impression cylinder; a third gear in fixed relation with said other impression cylinder and constantly meshing with said last mentioned gear; a fourth gear movable with said first impression cylinder; a fifth gear movable with said other impression cylinder and constantly in mesh with said fourth gear, said fourth and fifth gears being adapted to mesh with said first gear when their respective impression cylinders are in impression relation with said printing cylinder, said fourth and fifth gears being adapted to be rotatorially fixed relatively to their respective impression cylinders; and a driving gear constantly in mesh with said third gear and adapted to be rotatorially fixed relatively to said second gear. 36. In a rotary printing press, the combination with a printing cylinder; of two impression cylinders, the first impression cylinder being adapted to receive a sheet and to transfer the same to the other impression cylinder, said other impression cylinder being adapted to receive the sheet from said first cylinder; means for adjusting the first impression cylinder into and out of impression relation with said printing cylinder; means for adjusting the other impression cylinder into and out of impression relation with said printing cylinder; a first gear in fixed relation with said printing cylinder; a second gear in fixed relation with said first impression cylinder; a third gear in fixed relation with the other impression cylinder and constantly meshing with said last mentioned gear; a fourth gear having the same axis as and movable with said first impression cylinder; a fifth gear having the same axis as and movable with said other impression cylinder and constantly in mesh with said fourth gear, said fourth and fifth gears being adapted to be rotatorially fixed relatively to their respective impression cylinders; and a common driving gear constantly in mesh with said third gear and adapted to be rotatorially fixed relative to said second gear; and tripping mechanism for said printing cylinder having operable relation with said common driving gear. 37. In a rotary printing press the combination with a printing cylinder; of two impression cylinders, the first impression cylinder being adapted to receive a sheet and to transfer the same to the other impression cylinder, said other impression cylinder being adapted to receive the sheet from said first cylinder; means for adjusting the first impression cylinder into and out of impression relation with said printing cylinder; means for adjusting the other impression cylinder into and out of impression relation with said printing cylinder; a first gear in fixed relation with said printing cylinder; a second gear in fixed relation with said first impression cylinder; a third gear in fixed relation with said other impression cylinder and constantly meshing with said last mentioned gear; a fourth gear movable with said first impression cylinder; and a fifth gear movable with said other impression cylinder and constantly in mesh with said fourth gear, said fourth and fifth gears being adapted to mesh with said first gear.
- fixed relation with said printing cylinder; a second gear in fixed relation with said first impression cylinder; a third gear in fixed relation with said other impression cylinder and constantly meshing with said last mentioned gear; a fourth gear having the same axis as and movable with said first impression cylinder; a fifth gear having the same axis as and movable with said other impression cylinder and constantly in mesh with said fourth gear, said fourth and fifth gears being adapted to be rotatorially fixed relatively to their respective impression cylinders; and a driving gear constantly in mesh with said third gear and adapted to be rotatorially fixed relatively to said second gear. 38. In a rotary printing press, the combination with a printing cylinder; of two impression cylinders; means for adjusting the first impression cylinder into and out of impression relation with said printing cylinder; a first gear in fixed relation with said printing cylinder; a second gear in fixed relation with the first impression cylinder; a third gear in fixed relation with the other impression cylinder and constantly meshing with said last mentioned gear; a fourth gear movably mounted; a fifth gear movably mounted and constantly in mesh with said fourth gear; said fourth and fifth gears being adapted to mesh with said first gear when their respective impression cylinders are in impression relation with said printing cylinder, said fourth and fifth gears being adapted to be rotatorially fixed relatively to their respective impression cylinders; a common driving gear constantly in mesh with said third gear and adapted to be rotatorially fixed relative to said second gear; and tripping mechanism for said printing cylinder having operable relation with said common driving gear. 39. In a rotary printing press the combination with a printing cylinder; of two impression cylinders; means for adjusting the first impression cylinder into and out of impression relation with said printing cylinder; means for adjusting the other impression cylinder into and out of impression relation with said printing cylinder; a first gear in fixed relation with said printing cylinder; a second gear in fixed relation with said first impression cylinder; a third gear in fixed relation with said other impression cylinder and constantly meshing with said last mentioned gear; a fourth gear movable with said first impression cylinder; and a fifth gear movable with said other impression cylinder and constantly in mesh with said fourth gear, said fourth and fifth gears being adapted to mesh with said first gear.

when their respective impression cylinders are in impression relation with said printing cylinder, said fourth and fifth gears being adapted to be rotatorially fixed relatively to 5 their respective impression cylinders.

40. A rotary printing press including a printing couple having two cylinders; a driving gear for driving each cylinder; and registering mechanism having an element

connected with each of said cylinders, one of 10 said cylinders having a ledge engaging the base of the registering element connected with this cylinder.

In witness whereof, I hereunto subscribe my name this 19th day of February A. D. 15 1917.

ROBERT MIEHLE.

DISCLAIMER.

1,293,855.—*Robert Miehle*, Chicago, Ill. COMBINATION TWO-COLOR AND PERFECTOR PRINTING PRESSES. Patent dated February 11, 1919. Disclaimer filed December 5, 1925, by the patentee.

Hereby enters this disclaimer to that part of the claim in said specification which is in the following words, to wit:

40. A rotary printing press including a printing couple having two cylinders; a driving gear for driving each cylinder; and registering mechanism having an element connected with each of said cylinders, one of said cylinders having a ledge engaging the base of the registering element connected with this cylinder.

[Official Gazette December 29, 1925.]
